UNITED STATES PATENT OFFICE.

SEVERN D. SPRONG, OF BROOKLYN, NEW YORK, ASSIGNOR TO GENERAL ELECTRIC COMPANY, A CORPORATION OF NEW YORK.

MEANS FOR COOLING TRANSFORMERS.

Application filed May 4, 1925. Serial No. 27,655.

My invention relates to means for cooling transformers and more particularly to improved arrangements for cooling oil immersed transformers of the underground or manhole type. A great many transformers are located underground in manholes where they are connected to transmit power through underground cables. The load capacity of a transformer is limited by its temperature which is dependent upon the rate at which heat is generated in the transformer by the load and upon the rate at which this heat may be dissipated from the transformer. Any provision for increasing this rate of heat dissipation is therefore highly desirable as it will result in permitting the transformer to carry a greater maximum load without overheating.

The walls and floor of a manhole casing are in intimate contact with the surrounding earth which is often moist or otherwise of such character that it is a good conductor of heat. The general object of the invention is to provide an improved arrangement to take advantage of this fact to increase the cooling of an encased oil immersed transformer by circulating a suitable heat absorbing liquid such as the oil in contact with surfaces which are in good thermal relation with the manhole casing, whence heat may be given up to the cool earth surrounding the manhole.

The invention will be better understood from the following description taken in connection with the accompanying drawing in which Fig. 1 is a vertical sectional view of a manhole containing an encased transformer of the oil immersed type, the wall or casing of the manhole having a pipe or conduit embedded therein for the circulation and cooling of oil from the transformer casing; Figs. 2 and 3 are similar sectional views of manholes showing modified forms of the invention, and Fig. 4 is a detail sectional view on the line 4—4 of Fig. 3.

Like reference characters refer to similar parts in the different figures of the drawing.

In the particular arrangement shown in Fig. 1, the manhole comprises a floor 10, walls 11, and a top 12, the top having an opening with a cover 13 to permit access to the inside of the manhole. The manhole contains an encased transformer 14 of the oil immersed type. A pipe or conduit 15 is embedded at a convenient place in the man-

hole casing and connected through suitable valves 16 with the upper and lower parts of the casing of the transformer 14. As the oil in the casing of the transformer 14 is heated, it is thus permitted to flow by convection through the pipe or conduit 15 to be cooled before returning to the transformer.

In the arrangement shown in Fig. 2, a metal radiator 17 is secured to the inner face 65 of the manhole wall, a suitable cement or compound having good heat conducting qualities being used if desirable between the radiator and the wall to improve the heat conductivity between the oil in the radiator and the casing wall. The radiator 17 is connected through valves 16 with the upper and lower parts of the transformer casing 14 as in the arrangement shown in Fig. 1.

In the arrangement shown in Figs. 3 and 4, 75 a metal radiator 18 is built into and forms a section of the wall 11 of the manhole. This radiator 18 comprises an upper header 19 communicating with the upper part of the transformer casing 14 and a lower header 20 80 communicating with the lower part of the transformer casing. The headers 19 and 20 are spaced apart by a radiator section formed of two side walls of sheet metal 85 welded into the headers, the outer of these walls being corrugated, as shown in Fig. 4, to increase its area of contact with the surrounding earth.

The arrangement shown in Fig. 2 is particularly applicable in connection with manholes which are already built as the radiator 17 may be installed without disturbing the manhole casing. In the arrangements shown in Figs. 1 and 3, the parts for dissipating heat from the oil are built into the manhole 95 casing and are thus more particularly applicable when they may be installed during the construction of new manholes.

The invention provides a simple and efficient means for increasing the load capacity 100 of a transformer in a manhole and this is frequently of great advantage, particularly in manholes in large cities where it is often very difficult to provide sufficient transformer capacity in the limited space available.

What I claim as new and desire to secure by Letters Patent of the United States is:

1. An underground manhole, a transformer immersed in oil within a casing inside said manhole, heat radiating means having a sur-

- face in good thermal relation with the casing of said manhole, and means for conducting oil from the transformer casing into contact with said surface.
- 5 2. An underground manhole, a transformer immersed in oil within a casing inside said manhole, the casing of said manhole comprising a section having oil conducting passages, and means for conducting oil from
10 said transformer casing to said passages and back to said transformer casing.
3. An underground manhole, a transformer within a casing inside said manhole, heat radiating means having a surface in good thermal relation with the casing of said manhole, and means for conducting heat absorbing liquid from the transformer casing into contact with said surface.

In witness whereof, I have hereunto set my hand this 28 day of April, 1925.

SEVERN D. SPRONG.
